UNITED STATES PATENT OFFICE.

JAMES F. THAYER, OF PROVIDENCE, RHODE ISLAND.

BUTTON-FASTENER.

SPECIFICATION forming part of Letters Patent No. 276,645, dated May 1, 1883.

Application filed January 8, 1883. (No model.)

To all whom it may concern:

Be it known that I, JAMES F. THAYER, a citizen of the United States, residing at Providence, in the county of Providence and State 5 of Rhode Island, have invented certain new and useful Improvements in Button-Fasteners; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 My invention relates to an improved fastening for attaching buttons to shoes, &c.; and it consists of a fastener formed from hollow or tubular wire and adapted to be inserted through the fabric or material and clinched by a suitable setting-instrument.

20 To illustrate my invention I have selected one of staple form, although my improvement can be used as well in other forms of fasteners.

In the accompanying drawings, made enlarged, Figure 1 represents a perspective view 25 of a fastener, partly in section, as made from hollow round wire. Fig. 2 represents the same as attached to the fabric with a button and suitably clinched. Fig. 3 represents a modified form of hollow wire. Fig. 4 represents a modified form of clinching or securing a tubular staple, and partly in section.

Again referring to the drawings, A represents a staple provided with an eye, *a*, and 35 two downwardly-projecting prongs, *a'*, the whole made from hollow wire, as shown. Instead of leaving the ends of the prongs square, as shown, they can be chamfered or beveled off for more readily penetrating the material.

40 I am aware that round and other forms of solid wire have been used for button-fasteners; but the use of hollow or tubular wire for a button-fastener, so far as I know, is both new and novel.

45 Among the advantages possessed by a fastener made from hollow wire over solid wire

is lightness combined with great strength and stiffness, the value of tubular columns, &c., being well known in the mechanic arts. Another feature possessed by my fastener can be 50 shown in the process of clinching, whereby the prongs, after passing through the fabric and bent, are still further clinched by having the ends *a'* thereof flattened in the plane of the fabric, thereby presenting a broader holding- 55 surface to the fabric.

In the operation of attaching buttons to fabrics with my tubular fastener I pass one prong thereof through the eye *b* of the button B, when the fastener and button are both 60 placed in a jaw of a suitable setting-instrument, after which the latter is placed in position relatively to the fabric, the instrument being then made to pass or force the prongs through said fabric or material F and clinched 65 thereunder.

In Fig. 4 is represented another form of clinching a tubular fastener, whereby the ends *a'* thereof are upset or rolled over by suitable dies after passing the prongs through the 70 fabric.

Having thus described my invention, what I claim as new, and desire to secure by Letters Patent, is—

1. As an improved article of manufacture, a 75 button-fastener made from tubular or hollow wire bent into form, substantially as described and shown.

2. The button-fastener herein described, made from a piece of hollow wire, the ends 80 thereof bent so as to form the staple-shaped fastener A, consisting of an eye or loop, *a*, and two downwardly-projecting prongs, *a'*, the whole arranged and adapted to be used substantially as shown.

85 In testimony whereof I have affixed my signature in presence of two witnesses.

JAMES F. THAYER.

Witnesses:
